UNITED STATES PATENT OFFICE.

CHARLES EMANUELE, OF CLEVELAND, OHIO, ASSIGNOR OF ONE-HALF TO FRANK J. DEIBEL, OF CLEVELAND HEIGHTS, OHIO.

RESILIENT LIFT FOR BOOT AND SHOE HEELS.

Application filed August 29, 1923. Serial No. 659,909.

This invention, like that which constitutes the subject matter of my earlier application, Serial No. 636,515, filed May 4, 1923, relates to improvements in supplemental lifts of resilient material for use on heels of boots and shoes and commonly referred to as rubber heels.

The objects of my present invention are to produce a lift of the above mentioned character that is simple and economical of manufacture; that is made up of a body of rubber or the like having a cavity, and an insert of leather or similar material that is substantially the same shape as, but somewhat larger in area than, the cavity and which is adapted to be forced into the cavity and thereby impart to the lift the very desirable concavo-convex shape so that when the lift is applied to the boot or shoe heel and drawn down flat against the same, the edge portion of the lift is maintained in firm contact with the edge of the heel, and without the need of cement, thereby avoiding a separation at this point that would give to the heel an unsightly appearance; to form the cavity of such shape that a portion of the material of the lift remains of its normal thickness within the cavity and about which portion the insert extends so as to preserve the maximum of resiliency and wearing surface and thus prolong the life of the lift; to produce a lift of the aforesaid character that is particularly convenient of attachment; that permits a variable location of the nails that are used for holding the lift to the boot or shoe heel; and that allows for the use of small nails for attaching the lift particularly to wooden heels, such as the average French heel that is used so extensively on women's shoes, thereby eliminating the very common danger of splitting wooden heels when applying rubber lifts thereto.

These objects, with others hereinafter appearing, are attained in the construction illustrated in the accompanying drawing wherein Fig. 1 is a perspective view of my improved lift applied to a so-called French heel; Fig. 2 is a similar view of a larger size lift applied to the heel of a man's shoe; Fig. 3 represents a section on the line 3—3 of Fig. 2; Fig. 4 is a perspective view of the insert; Fig. 5 shows the insert and lift in section and in separated condition; and Fig. 6 shows them assembled.

In all essential respects, the lifts shown in Figs. 1 and 2 are the same, and their corresponding parts will be designated by the same reference characters. In each of these views and in Fig. 3, the shoe heel is designated A.

The supplemental lift 1 is of rubber or other suitable resilient material, and within its outer surface is formed a cavity 2. The cavity is of a depth enough less than the thickness of the lift to leave a substantial wall between its bottom and the under surface of the lift. Also, it is so shaped that a core 5 of the material of the lift, and of the normal thickness thereof, remains within the cavity.

An insert 6 of leather, or other substance suitable for the purpose, and of substantially the same shape as, but preferably of somewhat greater area than the cavity is adapted to be forced into the cavity so as to impart to the lift the concavo-convex condition illustrated in Fig. 6.

With the parts so assembled, the lift may be applied to the shoe heel A. Nails 7 are driven through the insert and into the shoe heel to draw the parts firmly together and hold them in such condition, the lift resuming and maintaining its former flat shape, but under tension, so that a tight joint between the adjacent edge portions of the lift and heel are assumed. It may also be explained that when the lift is forced to resume its flat condition with the insert in the cavity the edge portion of the lift, and the core 5, will be compressed and the wearing qualities of said parts thereby enhanced.

By using such material as leather for the insert 6 the nails 7 may be driven where it is found most convenient and they are not restricted to a definite location as is the case with rubber heels where washers are embedded therein which define the nail holes. This becomes especially important when replacing lifts as it allows the nails to be shifted somewhat from the location of the former nails thereby to miss the holes that are already in the heel. It will be understood that I do not limit myself to the use of leather for the insert 6, as other materials, such as compositions having somewhat the qualities of leather, or suitable metals, may be employed in lieu thereof.

It is apparent from this disclosure that my invention provides a supplemental lift

for heels of boots and shoes that is much cheaper and more simple of manufacture than prevailing types of rubber heels where metal washers have to be embedded in the 5 heels in the process of manufacture, and, in many instances, where the heels have to be made with concaved or dished under surfaces. On the other hand, with my simplified and cheapened construction, I have 10 many obvious advantages over the types of rubber heels heretofore used.

Having thus described my invention, what I claim is:

A heel lift of elastic material having a 15 three-sided cavity in its outer side, said cavity being of a depth enough less than the thickness of the lift to leave an integral, comparatively thick wall of the material be-

tween the bottom of the cavity and the inner surface of the lift, and an imperforate, open-center triangular insert of relatively non-elastic material adapted to be fitted within said cavity, said insert being considerably less in thickness than the cavity is deep and having a greater area than the normal area 20 of the cavity whereby when the insert is forced into the cavity it will impart a concavo-convex condition to, and in all directions throughout the entire area of, the lift, and attaching means adapted to be driven at 25 optional locations through the insert and the underlying wall of material.

In testimony whereof, I hereunto affix my signature.

CHARLES EMANUELE.
